UNITED STATES PATENT OFFICE.

JULIUS A. PEASE, OF NEW YORK, N. Y.

IMPROVEMENT IN SHIRT-BOSOMS.

Specification forming part of Letters Patent No. 40,426, dated October 27, 1863.

To all whom it may concern:

Be it known that I, JULIUS A. PEASE, of the city, county, and State of New York, have invented a new and Improved Shirt-Bosom; and I do declare that the following is a full and exact description of the same, reference being had to the accompanying drawings, and to the letters of reference marked thereon.

The nature of my invention consists in making a shirt-bosom of cloth or other material, enameled before or after it is made with water-proof enamel, and with springs to keep it smooth or make it resume a smooth position if bent.

To enable others skilled in the art to make and use my invention, I will proceed to describe its construction and operation.

I construct my bosom A in the usual form of what are termed "false bosoms," in the plaits B of which I place steel spring c lengthwise, and, if desired, crosswise, D, to prevent the

cloth from breaking or rumpling, said cloth or other material being water-proof enameled either before or after it is made up.

I do not confine myself to any style or shape, my object being to make a bosom that will retain or resume its smooth position after it is bent, and that can be wiped off with a wet towel when soiled and be ready for use. Neither do I confine myself to steel springs, as other material of a springy nature will answer the same purpose.

What I claim as my invention, and desire to secure by Letters Patent, is—

A shirt-bosom water-proof enameled, with springs to keep it in position, substantially as and for the purpose described.

JULIUS A. PEASE.
